P. G. MACGREGOR.
AUTOMATIC FIRE EXTINGUISHER.
APPLICATION FILED FEB. 13, 1913.

1,099,657.

Patented June 9, 1914.

UNITED STATES PATENT OFFICE.

PETER G. MACGREGOR, OF NEW YORK, N. Y., ASSIGNOR TO PYRENE MANUFACTURING COMPANY, A CORPORATION OF DELAWARE.

AUTOMATIC FIRE-EXTINGUISHER.

1,099,657.

Specification of Letters Patent. Patented June 9, 1914.

Application filed February 13, 1913. Serial No. 748,102.

To all whom it may concern:

Be it known that I, PETER G. MACGREGOR, a citizen of the United States, and resident of the city, county, and State of New York, have invented certain new and useful Improvements in Automatic Fire-Extinguishers, of which the following is a specification.

This invention relates to a device or attachment adapted to be used in connection with a tank, especially in connection with dyeing or cleaning apparatus in which the material is cleaned in a tank containing naphtha, gasoline or similar fluids, which are very inflammable and frequently become ignited and result in a disastrous and destructive fire which destroys the machinery and the goods contained therein.

The object of this invention is to provide a simple device which may be used in connection with these tanks and by means of which a fire extinguishing compound is automatically injected into the interior thereof when a fire occurs therein.

In carrying out the invention I provide a receptacle for the fire extinguishing compound which is mounted upon the tank in such a manner as not to interfere with its ordinary use. The receptacle is provided with means for automatically releasing the compound and for distributing the same throughout the interior of the tank and effectively extinguishing the fire.

In the drawings like parts in the several views have been given the same reference numerals.

Figure 1 is a sectional end elevation of a washing or cleaning tank showing a device mounted thereon. Fig. 2 is a sectional side elevation of the upper portion of Fig. 1, taken on the line 2-2 of the same. Fig. 3 is an enlarged sectional view of a portion of the device taken on the line 3-3 of Fig. 1. Fig. 4 is a top plan view of Fig. 3. Fig. 5 is a bottom plan view of Fig. 3. Fig. 6 is an enlarged detail sectional view of the lower valve support.

A washing or cleaning tank is shown at 1 and is provided with a removable cover 2. A revolving cylinder 3 is positioned in the tank 1 and operates in the usual manner in cleaning or washing the material by means of the naphtha or gasoline contained therein. It will be understood that these features of construction form no part of the invention and are shown herein for the purpose

of illustrating the invention as applied to the machine of this type.

A receptacle 4 is pivotally mounted at 5 upon the cover 2. A projection or latch 6 from the receptacle 4 is engaged by a pair 60 of crossed levers 7 and 8 which hold the receptacle 4 in its inoperative position, as shown in Fig. 1, against the action of a spring 9.

The crossed levers 7 and 8 are pivotally 65 mounted at 10 on the interior of the cover 2 and are held in their closed position by means of the fusible member 11 connecting the ends thereof. The opposite ends of the levers 7 and 8 are beveled, as shown in Fig. 3, 70 at the point where the same engage and hold the projecting latch 6 from the receptacle 4. Should a fire occur on the interior in the tank 1, the fusible member 11 will be melted and the pressure of the latch 6 75 against the beveled ends of these levers will separate the same and thus release the receptacle 4. The spring 9 swings the receptacle 4 about its pivot 5 to its upright position shown in dotted outline in Fig. 1. In 80 this position the lower end of the valve stem 12 passes through an opening in the cover 2 and engages a distributor plate 13 and opens the lower valve 14 and also the upper air valve or vent 15, allowing the fire extinguishing compound in the receptacle 4 to be injected into the tank over the distributor 85 plate 13.

The distributor plate 13 comprises a perforated member extending from end to end of 90 the tank and causes the fire extinguishing compound to be distributed throughout the interior of the same.

A temporary latch 16 may be provided for holding the receptacle 4 in its inoperative 95 position while the fusible member 11 is being attached to the holding lever 7 and 8, after which it is moved out of engagement therewith leaving the device set in position to be operated in the manner described. 100

It will thus be seen that a very simple attachment is provided which will operate automatically to inject the fire extinguishing compound into a tank when a fire occurs therein. 105

It will be understood that the details of construction may be changed to adapt the device for use with various forms of tanks, etc.

What I claim is:

In a device of the character described, a 110

support, a receptacle for a fire extinguishing compound hinged at one end to said support, an outlet for the fire extinguishing compound at one end of the receptacle, an air inlet at the other end thereof, valves for said inlet and outlet, a valve stem connected to said valves and having one end projecting through said outlet, means for holding the free end of said receptacle to said support, means for automatically swinging said receptacle upon its pivot when a fire occurs

whereby the projecting end of said valve stem engages said support and opens said inlet and outlet.

Signed at New York city, in the county 15 and State of New York, this 31st day of Jan., 1913.

PETER G. MACGREGOR.
